UNITED STATES PATENT OFFICE

JOHN O. MORRIS, DECEASED, LATE OF WASHINGTON, DISTRICT OF COLUMBIA, BY
CARRIE B. MORRIS, ADMINISTRATRIX, OF WASHINGTON, DISTRICT OF COLUMBIA,
ASSIGNEE, BY MESNE ASSIGNMENTS, TO TOBACCO STEMMING CORPORATION, OF
DOVER, DELAWARE, A CORPORATION OF DELAWARE

TOBACCO LEAF STEMMING AND STRAIGHTENING MACHINE

Continuation of application Serial No. 693,184, filed February 16, 1924. This application filed November 24, 1926. Serial No. 150,591.

It is a general object of this invention to provide a machine of this character that will be simple in construction, effective in operation, and that will reduce to a minimum 5 damage to the tobacco leaf passed through the machine.

A feature of the invention resides in the provision of feeding means comprising an endless band operatively associated with a 10 carding belt, the plane of said band being transverse to that of the belt; teeth on the edges of said band being adapted to mesh with teeth on the belt to effectively grip and convey tobacco stems to a stripping means. 15 Another feature of the invention relates to an improved arrangement of stripping elements adapted to draw the stem from the leaf and to crimp the leaf and thereafter to straighten it out. 20 A further feature provides a revolving suction drum in association with the conveying and stripping means operatively responsive to the completion of the stem drawing operation to pull the leaves from crimped 25 to substantially flat position. Control of the suction on the drum, so as to alternately draw the stems and the crimped leaves to flat position, results in retaining the leaves whole and effectively separates the stem 30 from the leaf fibres.

Other features including the provision of means for automatically removing the stripped leaves to a place of deposit will be apparent from the following description, 35 read in conjunction with the accompanying drawings in which:

Figure 1 is a top plan view partly diagrammatic of a machine embodying this invention.

40 Figure 2 is a front elevation of the same. Figure 3 is an end elevation.

Figure 4 is a fragmentary detail top plan view similar to Figure 1, the showing being partially diagrammatic and parts being removed in order to facilitate the disclosure.

Figure 5 is a detail front elevation similar to Figure 2, the showing being partially diagrammatic and parts being removed so as to reveal other parts of the mechanism.

50 Figure 6 is a fragmentary detail end ele-

vation similar to Figure 3, the showing being partially diagrammatic and parts being removed.

Figures 7 and 8 are views of carding belts of modified constructions.

This application is filed as a continuation of the application of John O. Morris, deceased, filed February 16, 1924, Serial No. 693,184.

Referring to the drawings for a detailed description of the illustrative embodiment of the invention there shown, a suitable frame 1 is made from stock material and suitably braced. An extension frame 2 is mounted on one end of the machine in the outer end of which is journaled an elongated idler carrier belt pulley 3, a companion idler pulley 4 being suitably journaled in the frame of the machine on the shaft 59. These pulleys carry the belts 5 and 6, while belt 8 is arranged in the plane of the belts 5 and 6 being also mounted at one end on the idler pulley 3, while the other end is mounted on a suitable idler pulley 9, the belt 8 extending the full length of the machine. These carrier belts 5, 6 and 8 are driven by suitable means and are timed to travel at the same speed.

The tobacco leaves 14 are spread into more or less open position by the operator on the carrier belts 5, 6 and 8 to the left of the stripping mechanism shown in Figure 1, and are carried by the belts to the stripping mechanism as more fully described below. In this connection it will be noted that the belt 8 dips downwardly to some extent as at 10 (Figs. 2 and 5) and lies flat on the underlying supporting surface 11 (Fig. 2). Since the belt 8 is driven by the pulley 3 through belts 5 and 6 and the upper stretch travels from left to right (Fig. 2), it will be observed that said upper stretch may be slightly slack so as to follow the supporting surface 11 and to dip downwardly at 10. Said belts 5, 6, at the extreme right ends thereof (Figs. 1 and 2) are positioned below the bottom of the stripping elements provided by the continuous band 15 and carding belt 18 so that the butt end of the stem 13 of the leaf 14 may be pressed down to the 100

bottom of the teeth or stripping elements 12 on the upper edge of the continuous band 15 as shown diagrammatically in Fig. 6. This stripping band is mounted on wheels 16 5 and 17 which are intermittently operated through the spiral gears 47, 48 (Fig. 5) by the intermittent driving gears shown diagrammatically at 39 and 40 (Figs. 1 and 4) whereby said band 15 is intermittently 10 driven as will be hereinafter more fully set forth.

As shown in Figs. 2 and 5, the carding belt 18 mounted upon pulleys 19 and 20 has on its outer face a series of very fine wire 15 carding teeth 12^a positioned for cooperative engagement with the teeth 12 of band 15. Said carding belt is dipped downwardly toward the teeth 12 of the stripping band 15 by means of the guide 20^a (Fig. 2) which is 20 adjustable by means of the adjusting nuts 21. This carding belt also is driven intermittently through intermittent driving gears 39 and 40 and gears 51 and 52 (Fig. 4) and is timed to run or operate simultaneously and 25 at the same speed with the tooth band 15, and simultaneously with belts 5, 6 and 8. Also, as shown in Fig. 4, a carrier belt 25 operates simultaneously with the band 15 and carrier belts 5, 6 and 8 being driven in 30 any appropriate manner as, for example, by means of a driving belt 44.

As is apparent in Figs. 1 and 2, the stripping band 15 is actually an endless belt mounted on wheels 16 and 17, and operating 35 in a plane perpendicular to that of carding belt 18. The carding belt is also endless and has its carding teeth intermeshing with the teeth of the stripping band (Figs. 5 and 6), the surfaces of the band and belt running 40 closely adjacent to each other for an interval. As shown in Figs. 1 and 2, the leaves to be stripped will feed on belts 5, 6 and 8 and when opposite the axis of wheel 17 will dip sufficiently to enable the stems to fall 45 within and between the adjacent parts of band 15 and belt 18 and be gripped and engaged by the teeth 12 of band 15 and teeth 12^a of belt 18. Band 15 and belt 18 operate at the same speed as the carrier belts 5, 6 and 50 8, and as the belts incline downwardly the stems will lodge within the gripping teeth. As the carrier belts reach their lower level, carding belt 18 (Fig. 2) then contacts with 55 or comes close to the edge of the band 15 and its fine wire carding teeth 12^a intermesh with the teeth 12 of the band to clamp the stems and carry them to the stripping rolls.

A pulley A is connected to a suitable 60 source of power by means of the belt B to operate the main drive shaft 34 through gears 32, 33.

As best shown in Figs. 4 and 5, a gear 35 is keyed to the drive shaft 34 and intermeshes with another gear 36, engaging a pinion 37 secured to one end of the lower-

most stripping roll 22, the uppermost stripping roll 22 having a companion pinion 38 intermeshing with the pinion 37 (Fig. 5) whereby the stripping rollers 22 are driven continuously in opposite directions from the 70 shaft 34.

An intermittent spiral gear wheel 39 is provided with gear teeth intermeshing with the teeth of the spiral pinion 40 mounted on the shaft 41, seated in the bearing 42. A 75 driving belt 44 is mounted on a pulley 43 fixed on shaft 41 and is also mounted on a pulley 45 on the shaft 46 on which the driving drum 73 for the carrier belt 25 is mounted. A spiral gear 47 is mounted on the shaft 49 to which is secured the wheel 16 carrying the toothed band 15. The wheel 16 thus drives the band 15 intermittently since the spiral gears 47, 48 are likewise driven intermittently through intermittent gears 39 and 40. 80 85

It will be understood that the intermittent driving gears 39 and 40 may be of any well known type for effecting intermittent drive. They are herein disclosed diagrammatically 90 merely, as the detail structure thereof is well-known. The main drive shaft 34 is driven continuously by the driving belt B.

As shown in Fig. 4 a gear wheel 51 is 95 mounted upon the shaft 41 meshing with the gear wheel 52. Said gear wheels 51 and 52 have interrupted movement through the intermittent gears 39 and 40, whereby for a period of time, these wheels will remain stationary. A shaft 53 secured to the gear wheel 52 extends toward the front of the machine and mounted thereon is the pulley 20 on which the carding belt 18 is mounted. The shaft 53 is journaled in a suitable bearing 54 mounted on the frame work of the machine. Therefore, the band 15 and the companion carding belt 18, both being driven from the intermittently running shaft 41, will travel intermittently in unison. 100 105

There is an opening 56 in the platform 110 11^a of the machine (Fig. 1) just above the vacuum drum 23.

Driving shaft 59 for the belt pulley 4 (Fig. 4) is driven intermittently from the intermittent spiral gears 39 and 40 by a 115 sprocket chain 55 from shaft 53 to shaft 59 which is journaled in suitable bearings 60 one of which appears in Fig. 2.

As seen in Figs. 1, 4, 5 and 6, an intermittent spiral gear 61 mounted upon the main drive shaft 34 intermeshes with the spiral gear 62 mounted on shaft 69, the inner end of which is mounted on the frame of the machine. These intermittent gears also may be of any well known type and are shown diagrammatically herein. The shaft 69 has secured to it a spur gear wheel 70 (Fig. 6) meshing with spur gear wheel 65 on shaft 63. On shaft 63 is mounted spiral gear 66 intermeshing with spiral 120 125 130

gear 67 secured to the journal of the vacuum drum 23, which is thus driven intermittently, but its periods of travel and rest are different from those of the carrier belts and stripper belts 15 and 18, as referred to below.

As shown in Figs. 2 and 5, an idler shaft 71 carries a belt idler pulley 72 on which the belt 25 is mounted, the other end of the belt 25 being mounted on a pulley 73 on shaft 46 which is driven by the belt 44.

A vacuum pump is preferably mounted apart from the stemming machine and may be driven continuously by a separate motor. An air line 75 is connected from the pump to the drum the vacuum being cut off at the proper time by a shutter or valve 29 which revolves with the drum.

It should be kept in mind as above stated that the main drive shaft 34 rotates continuously while the carrier belts 5, 6 and 8 and the stripper belts 15 and 18 travel intermittently by virtue of the intermittent driving gears 39 and 40. It should also be kept in mind that the leaf transferring and straightening suction drum 23 is also rotated intermittently by virtue of the intermittent driving gears 61 and 62. The timing, however, of the intermittent drum drive is different from that of the other intermittent drive whereby the drum performs its leaf straightening and transferring function while the stripper belts 15 and 18, as well as the carrier belts 5, 6, 8, etc., are at rest. The timing of the stripper belts 15 and 18 is preferably such that their travel is stopped soon after the leaf stem is entered between the continuously rotating stripper rolls 22 whereby the latter function to strip the stem from the leaf proper partly at least during a period of rest of the stripper belts 15 and 18. At the time that the suction drum is active in transferring and straightening the leaf, the intermittent drive gears 39 and 40 are inactive to effect their driving function whereby the movement of the band 15 and carding belt 18 is stopped as also are the carrier belts 5, 6, 8 and 25. When the suction drum 23 is thus active and in engagement with the tip end of the leaf the opposite or stem end of said leaf will be engaged and held by the strip teeth 12 and 12^a of the stripper belts 15 and 18. This action of the drum thus assures that the leaf will be straightened out and smoothed from its crimped position which it has previously assumed by the action of the stripping rollers and stripping belts as described. Also, it will be noted that this action of the suction drum occurs subsequently to the stripping action of the stripper rollers and belts. As clearly shown in Fig. 4, a sprocket chain 55 mounted upon a sprocket wheel 30 on the shaft 53 and a sprocket 31 on the shaft 64 drives the carrier belts 5 and 6 through intermeshing

gears 57 and 58 and the shaft 59 on which the belt driving pulley is mounted. The carrier belt 8 may, as shown, be driven by belts 5 and 6 through the common supporting pulley 3.

Gripping leaf stripping rollers 22 (Figs. 1, 4 and 5) are suitably mounted at one side of the carding belt 18. The rollers rotate oppositely to each other and grip the stems fed by the intermeshing teeth of belt 18 and tooth band 15. The line of contact of the rollers is slightly below the line of contact of the intermeshing teeth 12 and 12^a so that the stems will incline and be more readily drawn within the rollers as they are conveyed to them. The stem gripping rollers will draw the stems laterally of the carrier belts 5, 6, 8, and tend to crimp the leaves toward and against the teeth in which they are engaged on the side thereof away from the rollers.

If this action were to continue, the stem and leaf fibres attached to the stem would be completely pulled from the leaf and the torn crimped leaf would be left bunched and wedged in the intermeshing teeth 12 and 12^a of the band 15 and carding belt 18.

To avoid this condition a vacuum drum 23 is provided and positioned on the other side of the line of contact of the carding belt 18 and band 15 (Figs. 1 and 4). In other words, drum 23 and stripping rollers 22 are situated abreast of each other on opposite sides of the gripping conveying means 15 and 18. Drum 23 is adapted to rotate counterclockwise as viewed in Fig. 3 so that a point on the drum will first pass the stem of a gripped leaf before passing the body thereof. As illustrated in Fig. 1, the drum has a series of suction openings or ports 24 and a vacuum supply is provided for creating a suction within the drum. The ports are timed in their travel to reach the crimped portion of the leaves the moment the stripping action has proceeded sufficiently to loosen the stem from the leaf. The suction on the ports together with peripheral movement of the drum due to rotation will cause a pulling of leaf 14 from the stem at the same time the stripping rollers 22 have completed loosening the stem and slightly crimped the leaf against the teeth. Thus the suction drum will take hold of the tip of the leaf and pull the leaf to a straight, flat position, while the opposite end of the leaf and the stem are held by the teeth.

When the leaf has been pulled substantially its length by the action of the suction drum, the butt end will be completely withdrawn by the rollers 22 from between the teeth of the band 15 and belt 18 without damage to the leaf. At this point, the feeding mechanism ceases to operate by virtue of its intermittent drive, while the

drum 23 carries the leaf around until it is positioned above belt 25, whereupon the air is cut off by a shutter or valve 29 (Fig. 3) which revolves with the drum. The leaf, being free from suction will drop from the drum to endless belt 25 and be conveyed to a suitable place of deposit. The drum may be adjusted so that the air ports 24 will engage the leaf at any desired point in the stem pulling operation of the stripping rollers. Since the drum 23 and feeding mechanism 5, 6, 8, etc., operate intermittently, and the stripping rolls 22 operate continuously, being driven from the gear 35 on main drive shaft 34, the stripping arrangement may be regulated for different grades of tobacco, to afford a pull in one direction of varying duration prior to the application of suction on the leaves. 20 A suitable wiping pad 26 (Fig. 3) is mounted to wipe on the drum to clean its surface of any particles of tobacco or foreign matter that may be adhering thereto. Guide plate 28 positioned in front of the drum assures the deposition of the leaves from the drum on the belt 25. Endless belt 25 conveys the stemmed leaves to a desired place of deposit.

In Figure 7 I have illustrated an arrangement in which two intermeshing carding belts 50' are employed to convey the leaf to stemming position and hold the leaf while the stripping rolls 22 strip the stem from the leaf. The second carding belt takes the place of toothed band 15. Figure 8 shows the interengagement between the wires on the belts 50'.

Since certain changes may be made in the above construction and different embodiments of the invention could be made without departing from the scope thereof, it is intended that all matter contained in the above description or shown in the accompanying drawings shall be interpreted as illustrative and not in a limiting sense.

What is claimed is:

1. A tobacco stemming machine including intermittently operated stem gripping means, continuously operated stemming rolls and intermittently operated suction means to convey the stemmed leaf away from said gripping means, said rolls and suction means being arranged on opposite sides of the gripping means.
2. A leaf stemming machine including, in combination, leaf feeding means, leaf gripping means, means for operating said feeding and gripping means interruptedly but simultaneously, continuously operated stripping rolls, leaf straightening means including a suction drum, said suction drum and stripping rolls being on opposite sides of the leaf gripping means, a conveyor for the straightened leaf, said leaf straightening means and said conveyor operated inter-

mittently and only when the said feeding and gripping means are idle.

3. A leaf stemming machine including, in combination, intermittently operated leaf feeding means and stem gripping means including leaf anchoring teeth, continuously operating stemming rolls, intermittently operated leaf straightening means including a rotatable drum, cooperating with said anchoring teeth to extend the leaf to a substantially straightened position, said drum being arranged to grip the leaf after the stemming rolls have pulled the stem to a predetermined degree.

4. A leaf stemming machine including, in combination, intermittently operated leaf feeding means and stem gripping means including leaf anchoring means, continuously operating stemming rolls engaging the leaf stem and pulling it to crimp the leaf against said gripping means, intermittently operated leaf straightening suction means, cooperating with said anchoring means to extend the leaf to a substantially straightened position after said crimping thereof, said stemming rolls and suction means being positioned on opposite sides of the leaf anchoring means, and means including said suction means to convey the stemmed leaf from the machine.

5. A leaf stemming machine including, in combination, intermittently operated stem gripping means including a pair of carding belts movable in planes perpendicular to each other, continuously operated stemming rolls, and an intermittently operated drum having suction ports whereby the stemmed leaves are temporarily held on said drum and conveyed to a point of delivery at which point the suction is released and the leaf dropped from the drum.

6. A leaf stemming machine including, in combination, intermittently operated feeding belts, leaf stripping means, continuously operated stemming rolls, said belts and stripping means being timed for simultaneous intermittent operation, a stemmed leaf conveyor, and means intermittently operating said conveyor only when the feeding belts and stripping means are at rest.

7. A leaf stemming machine including, in combination, stem gripping means intermittently operated, means for pulling the stems and crimping the leaves against said gripping means, leaf straightening means including a suction drum intermittently operated to straighten the crimped stemmed leaves, and means operating said straightening means only while the gripping means are idle.

8. A leaf stemming machine including, in combination, continuously operated stemming means, intermittently operated leaf gripping means to convey the leaf to the stemming means, and leaf straightening

means including said gripping means for holding the butt end of the leaf, and an intermittently operated suction member engaging the other end of the leaf and drawing it in the opposite direction away from the butt end.

9. A tobacco stemming machine including continuously operated stemming means, intermittently operated stem gripping means 10 to convey the stem to the stemming means, and leaf straightening means including said gripping means for holding the butt end of the stemmed leaf, a drum having suction ports in its periphery to engage the leaf 15 whereby the tip end of said leaf is held on the drum when suction is applied, and means for controlling said drum to draw said tip end of the leaf away from its butt end subsequently to stemming action of said stemming means.

10. A leaf stemming machine including, in combination, traveling leaf gripping means, stripping means for drawing the stems in a direction transverse to the line of travel of 20 the gripping means, a suction drum for holding a leaf and rotating in a direction to exert a pull upon a leaf held by said gripping means in a direction transverse to and away from the latter, and timing means 25 whereby a leaf to be stemmed will be carried to the stripping means and have its stem pulled to crimp the leaf toward the gripping means, whereupon said suction drum will engage and hold the body of the 30 leaf and draw it from the stem into substantially flat condition.

11. In a leaf stemming apparatus, in combination, leaf engaging stripping elements, means for stripping the leaf stem from the 40 leaf when held by said stripping elements, and a traveling suction drum positioned abreast of said stripping means and engaging the leaf and transferring it subsequently and oppositely to the stripping action of 45 said stripping means.

12. In a leaf stemming apparatus, in combination, leaf engaging stripping elements, means for stripping the leaf stem from the leaf when held by said stripping elements, 50 a traveling suction drum positioned abreast of said stripping means and engaging the leaf and transferring it subsequently and oppositely to the stripping action of said stripping means, and means intermittently driving said stripping elements and said drum in alternation.

13. In a leaf stemming apparatus, in combination, leaf engaging stripping elements, means for stripping the leaf stem from the 60 leaf when held by said stripping elements, a traveling suction drum positioned abreast of said stripping means and engaging the leaf and transferring it subsequently and oppositely to the stripping action of said 65 stripping means, means intermittently driv-

ing said stripping elements and said drum in alternation, and means continuously driving said stripping means.
